CLAIM

The ornamental design for a combination deodorizer
and light, as shown and described.

DESCRIPTION

FIG. 1 is a perspective view of the combined deodorizer
and light showing our new design, the ceiling
shown in broken lines for illustrative purposes only;
FIG. 2 is a bottom plan view thereof on an enlarged
scale with respect to FIG. 1;

FIG. 3 is a left side elevational view on an enlarged
scale with respect to FIG. 1; and

FIG. 4 is a front side elevational view thereof on an
enlarged scale with respect to FIG. 1.

FIG. 1

FIG. 2

FIG. 3

FIG. 4
